Des. 217,481
Patented May 5, 1970

217,481

HAIR CURLING TOY

Terry L. Bernard, Cincinnati, Ohio, assignor to Kenner Products Company, Cincinnati, Ohio, a corporation of Delaware

Filed Nov. 14, 1968, Ser. No. 14,470

Term of patent 14 years

Int. Cl. D21—02

U.S. Cl. D34—15

FIG. 1 is a side elevational view of the hair curling toy showing my new design;

FIG. 2 is a top plan view thereof; and
FIG. 3 is a bottom plan view thereof.

I claim:

The ornamental design for a hair curling toy, substantially as shown.
